UNITED STATES PATENT OFFICE.

NICHOLAS F. BECKER, OF CINCINNATI, OHIO, ASSIGNOR TO CHARLES DICKINSON, OF CHICAGO, ILLINOIS.

AUTOMATIC SACK FILLING AND SEWING MACHINE.

SPECIFICATION forming part of Letters Patent No. 608,567, dated August 9, 1898.

Application filed March 1, 1897. Serial No. 625,654. (No model.)

To all whom it may concern:

Be it known that I, NICHOLAS F. BECKER, a citizen of the United States, residing in Cincinnati, in the county of Hamilton and State of Ohio, have invented a new and useful Improvement in Automatic Sack Filling and Sewing Machines, of which the following is a specification.

My invention relates to improvements in sack filling and sewing machines.

The object of my invention is to provide an automatic machine of a simple, durable, and efficient construction, of a compact form, so it will occupy little space in the warehouse or mill, and by means of which sacks or bags may be cheaply and rapidly filled and the filled sacks sewed and discharged from the machine.

The machine embodying my invention comprises an intermittently-revolvble carrier or turn-table upon which are mounted a series of opening and closing sack-holders, the same being preferably four in number, so that a sack may be placed in one holder while a sack in another holder is being filled, that in another sewed, and that in the remaining holder released or discharged, all simultaneously; a sewing mechanism mounted upon a reciprocating carriage and operating to sew the filled sack in one of the holders; a sack-filling mechanism or spout for delivering the material into the sack; a shaker or device for compacting the material in the sack; mechanism for automatically opening the holders at suitable intervals and locking them open; mechanism for automatically closing the holders and locking them closed at suitable intervals; and mechanism for automatically imparting a step-by-step movement to the holder-carrier and locking it in position for the several holders thereon to properly register and coöperate with the other devices; and mechanism for automatically operating the sewing mechanism while its carriage is traveling forward.

My invention consists in the novel construction of parts and devices and in the novel combinations of parts and devices herein shown and described, and specified in the claims.

In the accompanying drawings, forming a

part of this specification, and in which similar letters of reference indicate like parts in all the views, Figures 1 and 1^a, taken together, are a side elevation of a machine embodying my invention. Fig. 2 is a plan view. Fig. 3 is a section on the line 3 3 of Fig. 2, showing the sewing device. Fig. 4 is a bottom plan view of the sewing device. Fig. 5 is a section on the line 5 5 of Fig. 3. Fig. 6 is a detail view of the shifting-gear for throwing the sewing mechanism in and out of gear. Fig. 7 is a detail side view of the shaker. Fig. 8 is a section on the line 8 8 of Fig. 7. Fig. 9 is a detail end view of parts herein-after to be described. Fig. 10 is a detail plan view of one of the holders and mechanism for locking it closed. Fig. 11 is a section on the line 11 11 of Fig. 10. Fig. 12 is an enlarged side elevation of the sewing mechanism. Fig. 13 is an enlarged plan view of the sewing mechanism, and Fig. 14 is a detail perspective view of the mutilated gears.

In the drawings, A represents the frame of the machine.

B is the intermittently-movable carrier, upon which the sack-holders are mounted, the same being preferably in the form of a revolving wheel or turn-table sufficiently large in diameter to enable four sacks to be simultaneously suspended from it. The carrier B is provided with four openings B', over or adjacent to which the sack-holders are located, said openings being preferably of a diamond shape.

B² is the pedestal or support, upon which the carrier B rotates, and B³ is the shaft, to which the carrier is secured and which is journaled in said pedestal.

C C' are bars secured at their outer ends to the frame and supported at their inner ends by the upper end of the shaft B³, which is extended up through the carrier for this purpose. The bars C C' are located above the carrier and are furnished with pins or projections c to open and c' to close the holders and their locking devices as the same pass under these bars in the rotary movement of the carrier.

D D are the opening and closing sack-holders, the same consisting, preferably, each of four bars d d, hinged together at their meet-

ing ends by pivots d' and d^2 and provided with suitable sack-holding hooks or devices d^3 for suspending the sack therefrom. Each of the holders D or its two end pivots d' d' is 5 adapted to reciprocate in guide-slots b b in the carrier B as the holder opens and closes, and the two middle pivots d^2 d^2 of the holder are connected to two reciprocating slides b' b' , mounted to reciprocate radially in or on 10 suitable guides b^2 b^2 on the carrier B. The slides b' are provided with notches b^3 , which are engaged by pawls or latches b^4 , pivoted on the carrier, and which serve to lock the holder in its open position, and the slides 15 b' are also furnished with notches b^5 , that are engaged by the same pawls, so as to lock the holder in its closed position. The pawls b^4 are furnished with springs b^6 , that serve to throw them into engagement with said notches 20 and to hold them in such engagement. The pawls are also provided with suitable pins or projections b^7 , which engage suitable pins or projections c^2 c^2 on the arm C' to retract the pawls, and thus permit the holder D to open.

25 The holder D is opened automatically when the pawls are retracted by coiled springs d^4 , with which the holders are provided. The holders are automatically closed by cams, inclines, or projections d^5 , with which the holders are provided, engaging pins, projections, or rollers c^3 c^3 on the arm C.

E is the filling device.

The filling device may be of any suitable construction. As illustrated in the drawings 35 it consists of a spout or hopper located above the holder-carrier.

F is the shaker or device for settling or compacting the material in the bag as it is filled. It may be of any suitable construction. As illustrated in the drawings it consists, essentially, of an up-and-down vibrating table adapted to lift the bag on its upward movement and drop it suddenly on its downward movement, so as to settle and compact the material therein.

45 The shaker F is thus vibrated or moved up and down by means of two eccentrics F' on the shaft F², which revolve in blocks F³, that slide in yokes F⁴, pivoted to the frame, and upon which sliding blocks the shaker F rests. By this means the sack is given not only an up-and-down movement, but a slight lateral movement, which aids in settling and compacting the material in the sack.

55 G is a reciprocating or traveling carriage upon which the sewing mechanism is mounted and by which the sewing mechanism is moved or fed forward from one end of the seam to be formed in the sack to the other.

60 This sewing-carriage G slides upon suitable guides G' G', secured to the frame of the machine above the carrier B. The sewing-carriage G is reciprocated or moved back and forth along said guides by a revolving screw G², which engages or revolves in a nut G⁴, attached to the carriage G. Mounted in a dovetail guide g¹² in the sewing-carriage G is a re-

ciprocating slide g, by which the looper II and needle K are operated. The slide g is reciprocated back and forth on the carriage 70 G by means of a vibrating rod g', that engages pins or projections g² on the slide g, and which rod is secured to arms g³ on the rock-shaft g⁴. The rock-shaft g⁴ is caused to rock by being furnished with an arm g⁵, having a slot g⁶, in which travels a sliding block g⁷, through which is inserted a crank g⁸, journaled loosely on the end of the screw G². The crank g⁸ is furnished with a pivoted pawl g⁹, which engages a ratchet g¹⁰, that locks the 80 crank to the screw-shaft when the screw-shaft is turned in one direction, and thus causes the shaft to rock, while permitting the screw-shaft to turn in the opposite direction without turning the crank. A spring g¹¹ holds 85 the pawl in engagement with the ratchet. By this mechanism it will be seen that the needle-operating slide g will be actuated or reciprocated by the revolution of the screw-shaft itself when the screw is being rotated 90 in one direction and that it will be out of gear with the screw-shaft when said screw-shaft is turned in the other direction. The screw-shaft G² is rotated first in one direction and then in the opposite direction to cause the 95 sewing-carriage G to travel back and forth, as required. The rotation of the screw-shaft is automatically reversed when the sewing-carriage reaches the end of its travel in either direction by means of a sliding sleeve G³, 100 furnished with two gears G⁵ G⁵, adapted to engage the driving-gear N, the one or the other. This sleeve is splined to the screw-shaft, so as to rotate with it, and it is reciprocated on the screw-shaft to throw one of its 105 gears into and the other out of engagement with the driving-gear by means of a slide G⁶ on the rock-shaft g⁴, which is furnished with arms G⁷, adapted to be engaged by the sewing-carriage G when it reaches the limit of 110 its movement at either end.

The looper II is provided with an eye or hole h near its end, through which the thread passes, so that the looper may by its vibratory movement at intervals, as required, press 115 the thread against the needle K and into the recess, slit, or notch with which the needle is provided. The looper II is secured to or made integral with a vibrating arm II', which is secured to or made integral with a rock-shaft II², journaled in suitable bearings II³ on the sewing-carriage G. This rock-shaft 120 II² is hollow or in the form of a sleeve, and it is provided at its rear end with an enlarged or collar portion II⁴, which is provided with 125 a spiral groove or cam h', that is engaged by a pin h², fixed to a sleeve h³, reciprocating inside the sleeve or rock-shaft II², so that a vibratory or swinging movement may be communicated to the looper II and its operating-arm and rock-shaft by the reciprocation of the sleeve h³ inside the sleeve II². The reciprocating sleeve h³ is provided with a longitudinal slot h⁴ and with an adjustable col-

lar or stop h^5 and is itself reciprocated by a pin h^6 on the slide or arm h^7 , which is connected at h^8 to the reciprocating needle and looper operating slide g on the needle-carriage 5 G. By adjusting the collar or stop h^5 on the slotted sleeve h^3 backward or forward the looper may be made to pause a shorter or longer interval in position to hold the thread against the needle K, as required.

10 The needle K is provided with a slot or hook k to receive the thread, and the lip k' of the hook is depressed below or within the general surface of the needle back of the lip, so that the edge or point of the lip will not catch 15 upon the fabric or interfere with the withdrawal of the needle from the fabric, while at the same time serving to uniformly and securely catch the thread when the thread is pressed by the looper into the bevel or recess 20 k^2 just back of the lip. The needle K is secured in a hinged or yielding needle-holder K', pivoted to the needle-operating slide g at K ^{2} , so that the needle may have a slight tilting or yielding movement to prevent lateral 25 strain thereon and compensate for the continuous forward movement of the sewing-carriage G in respect to the stationary sack X, held in the holder D. A torsional spring K ^{3} , secured to the needle-operating slide g and 30 bearing against the needle-holder K', serves to return the needle-holder K' into a straight line with or parallel to the needle-operating slide g after the needle is withdrawn from the sack.

35 The filling device E is provided with a cut-off slide or valve E ^{2} below the hopper E' and a similar valve or slide E ^{3} above the hopper, which slides or valves are operated simultaneously by a common lever E ^{4} to which the slides are connected by pivoted links E ^{5} . The hopper E' should be made of a size corresponding to that of the sack to be filled, so as thus to measure the material into each sack.

40 E ^{6} is the delivery-spout, by which the material to be sacked is delivered first into the hopper E' and then through the filling-spout E into the sack.

45 Motion is communicated to the shaker-operating shaft F ^{2} from the driving-shaft M by means of a belt M', which passes around pulleys M ^{2} on the driving-shaft and M ^{3} on the shaker-shaft F ^{2} .

50 The driving-gear N, which communicates motion to the screw-shaft G ^{2} , first in one direction and then in the other, by alternately engaging the gears G ^{5} G ^{6} on the sliding sleeve G ^{3} , is secured to an upright counter-shaft N'. A continuous rotary motion is communicated to this counter-shaft N' from the driving-shaft M through suitable connecting-gearing. The connecting-gearing may preferably consist of a belt M ^{4} , running on the pulley M ^{5} on the driving-shaft M and over a pulley P' on the counter-shaft P, which is furnished with a gear P ^{2} , that meshes with a gear N ^{2} on a counter-shaft N ^{3} , which is provided with a bevel-gear N ^{4} , that meshes with a bevel-gear

N ^{5} on the counter-shaft N ^{6} , which has a bevel-gear N ^{7} meshing with a bevel-gear N ^{8} on the lower end of the upright counter-shaft N'. 70

The necessary intermittent or step-by-step rotary movement may be communicated to the sack-holder carrier B from the driving-shaft and the carrier intermittently locked stationary and in position for the holders D D D D, mounted thereon, to register one with the sack filling and shaking mechanisms, one with the sack-sewing device, one at the filled and sewed sack discharging station or discharge-chute R, and one at the station 80 where the sacks are inserted in the open holder by any suitable connecting gearing or mechanism. The mechanism which I prefer to employ, however, for so intermittently revolving and locking the holder-carrier B in position consists in a mutilated gear B ^{4} , secured to or made integral with the holder-carrier or its shaft, and a corresponding mutilated gear P ^{3} on the counter-shaft P. The mutilated gear B ^{4} is furnished with locking projections B ^{5} , which engage the smooth locking-face P ^{4} of the mutilated gear P ^{3} , and thus positively lock the carrier B in position. 85

The sewing-carriage G is preferably provided with guides G ^{9} G ^{10} , between which the mouth or upper edges of the sack pass to hold the same in position while the needle is being thrust through and withdrawn from the same. These guides act as presser-feet and are furnished with holes or perforations for the needles to pass through. 95

I claim—

1. In a sack filling and sewing machine the combination with a series of opening and closing sack-holders, of an intermittently-movable carrier upon which said holders are mounted, a traveling sewing-carriage provided with a sewing device or mechanism mounted thereon, a sack-filling device, a shaker, means for opening and closing the holders, means for locking the holders open and closed, means for intermittently moving and locking the holder-carrier in position, means for operating the sewing device on said traveling sewing-carriage, and means for operating the shaker, substantially as specified. 105

2. The combination with a series of opening and closing sack-holders for holding the sack open while being filled and closed while being sewed, of an intermittently-movable carrier upon which said holders are mounted, and a traveling sewing-carriage provided with a sewing mechanism, substantially as specified. 110

3. The combination with an intermittently-movable sack-holder carrier for holding the sack open while being filled and closed while being sewed, of a sack-holder mounted on said carrier, and a traveling sewing device, substantially as specified. 115

4. The combination with a series of opening and closing sack-holders for holding the sack open while being filled and closed while being sewed, of an intermittently-movable

carrier upon which said holders are mounted, a traveling sewing-carriage provided with a sewing mechanism, and a sack-filling device, substantially as specified.

5 5. The combination with a series of opening and closing sack-holders for holding the sack open while being filled and closed while being sewed, of an intermittently-movable carrier upon which said holders are mounted, 10 a traveling sewing-carriage provided with a sewing mechanism, a sack-filling device, and a shaker, substantially as specified.

6. The combination with a sack-filling device, of a series of movable sack-holders for 15 holding the sack open while being filled and closed while being sewed, and a traveling sewing device, substantially as specified.

7. The combination with a sack-filling device, of a series of movable sack-holders for 20 holding the sack open while being filled and closed while being sewed, a traveling sewing device, and a carrier for intermittently moving the holders successively from the filling device to the sewing device, substantially as 25 specified.

8. The combination with a sack-filling device, of a series of movable sack-holders for holding the sack open while being filled and closed while being sewed, a traveling sewing 30 device, a carrier for intermittently moving the holders successively from the filling device to the sewing device, and a sack-shaking device, substantially as specified.

9. The combination with an intermittently- 35 rotating sack-holder carrier, of a series of opening and closing sack-holders mounted thereon, locking devices on said carrier for automatically locking the holders in their open and closed positions, and means for automatically operating or releasing said locking 40 devices as the carrier rotates, substantially as specified.

10. The combination with an intermittently-rotating sack-holder carrier, of a series of opening and closing sack-holders mounted thereon, means for automatically opening and closing the holders, and locking devices on said carrier for automatically locking the holders in their open and closed positions, and means for automatically operating or releasing said locking devices as the carrier rotates, substantially as specified.

11. The combination with an intermittently-rotating sack-holder carrier, of a series of opening and closing sack-holders mounted thereon, means for automatically opening and closing the holders, locking devices on said carrier for automatically locking the holders in their open and closed positions, means for automatically operating or releasing said locking devices as the carrier rotates, and a sack-filling device, substantially as specified.

12. The combination with an intermittently-rotating sack-holder carrier, of a series of opening and closing sack-holders mounted thereon, means for automatically

opening and closing the holders, locking devices on said carrier for automatically locking the holders in their open and closed positions, and means for automatically operating or releasing said locking devices as the carrier rotates, a sack-filling device, and a traveling sack-sewing mechanism, substantially as specified.

13. The combination of a revolving sack-holder carrier, provided with guides for an opening and closing sack-holder, with an opening and closing sack-holder moving in or on said guides in opening and closing, the 80 guides on the carrier at two of the pivots of the holder being guideways or channels, and at the other two pivots of the holder being reciprocating slides, substantially as specified.

14. The combination of a revolving sack-holder carrier, provided with guides for an opening and closing sack-holder, with an opening and closing sack-holder moving in or on said guides in opening and closing, the guides on the carrier at two of the pivots of 90 the holder being guideways or channels, and at the other two pivots of the holder being reciprocating slides, and pawls or latches on the carrier engaging said guide-slides for locking the holder in its open and closed positions, substantially as specified.

15. The combination with a revolving sack-holder carrier of an opening and closing sack-holder mounted thereon, reciprocating guide-slides on the carrier and connected to the 100 holder, said guide-slides being provided with notches and pawls or latches on the carrier engaging said guide-slides, substantially as specified.

16. The combination with a revolving sack-holder carrier of an opening and closing sack-holder mounted thereon, reciprocating guide-slides on the carrier and connected to the holder, said guide-slides being provided with notches and pawls or latches on the carrier 110 engaging said guide-slides, and stationary cams or projections for operating said pawls or latches as the carrier revolves, substantially as specified.

17. The combination with a revolving sack-holder carrier of an opening and closing sack-holder mounted thereon and provided with cams or inclines d^5 d^5 on two of its hinged bars, and stationary projections engaging said cams or inclines on said holder to close 120 the same as the carrier revolves, substantially as specified.

18. The combination with a revolving sack-holder carrier of an opening and closing sack-holder mounted thereon and provided with 125 cams or inclines d^5 d^5 on two of its hinged bars, stationary projections engaging said cams or inclines on said holder to close the same as the carrier revolves, guide-slides on the carriers and connected to the holder, 130 and pawls or latches on the carrier engaging said guide-slides to lock said holder closed, substantially as specified.

19. The combination with an intermit-

tently-movable sack-holder carrier, of a sack-holder mounted thereon, a traveling sewing-carriage, a screw for reciprocating said carriage, a reciprocating needle and looper operating slide mounted on said sewing-carriage, a needle operated by said slide, a vibrating looper mounted in said sewing-carriage, and connecting mechanism for vibrating said looper by the reciprocation of said slide, substantially as specified.

20. The combination with an intermittently-movable sack-holder carrier, of a sack-holder mounted thereon, a traveling sewing-carriage, a screw for reciprocating said carriage, a reciprocating needle and looper operating slide mounted on said sewing-carriage, a needle operated by said slide, a vibrating looper mounted in said sewing-carriage, connecting mechanism for vibrating said looper by the reciprocation of said slide, and connecting mechanism for operating said slide from or by the revolution of said screw, substantially as specified.

21. The combination with a reciprocating slide of a needle connected therewith, a vibrating looper, a looper-operating rock-shaft provided with a spiral groove or cam, a reciprocating sleeve provided with a pin or projection engaging said spiral groove or cam and connected with said reciprocating slide, substantially as specified.

22. The combination with a traveling sewing-carriage G of guides G' therefor, nut G⁴, screw G², transversely-reciprocating needle and looper operating slide g provided with pins or projections g², rock-shaft g⁴ having arms g³ furnished with vibrating bar g' engaging said projections g², slotted arm g⁵ on said rock-shaft, sliding block g⁷, crank g⁸ journaled loosely on said screw and passing through said sliding block, and pawl g⁹ and ratchet g¹⁰ for locking said crank to said screw-shaft, when it revolves in one direction but not in the other, substantially as specified.

23. The combination with a traveling sewing-carriage G of guides G' therefor, nut G⁴, screw G², transversely-reciprocating needle and looper operating slide g provided with pins or projections g², rock-shaft g⁴ having arms g³ furnished with vibrating bar g' engaging said projections g², slotted arm g⁵ on said rock-shaft, sliding block g⁷, crank g⁸ on said screw-shaft and passing through said sliding block, substantially as specified.

24. The combination with a traveling sewing-carriage G of guides G' therefor, nut G⁴, screw G², transversely-reciprocating needle and looper operating slide g provided with pins or projections g², rock-shaft g⁴ having arms g³ furnished with vibrating bar g' en-

gaging said projections g², slotted arm g⁵ on said rock-shaft, sliding block g⁷, crank g⁸ journaled loosely on said screw and passing through said sliding block, and pawl g⁹ and ratchet g¹⁰ for locking said crank to said screw-shaft, when it revolves in one direction but not in the other, a driving-gear N, and sliding sleeve G³ on said screw-shaft G² furnished with gears G⁵ G⁶ adapted to alternately engage the driving-gear and reverse the motion of the screw-shaft, substantially as specified.

25. The combination of an intermittently-movable sack-holder carrier and an opening and closing sack-holder mounted thereon, with a traveling sewing-carriage, a screw for reciprocating said sewing-carriage, a transversely-reciprocating needle-operating slide mounted on said carriage, and connecting mechanism between the screw and said needle-slide to operate the needle-slide from or by the screw, substantially as specified.

26. The combination of an intermittently-movable sack-holder carrier and an opening and closing sack-holder mounted thereon, with a traveling sewing-carriage, a screw for reciprocating said sewing-carriage, a transversely-reciprocating needle-operating slide mounted on said carriage, connecting mechanism between the screw and said needle-slide to operate the needle-slide from or by the screw, a vibrating looper, and connecting mechanism for operating the looper from or by said needle-slide, substantially as specified.

27. The combination with a traveling sewing-carriage G of guides G' therefor, nut G⁴, screw G², transversely-reciprocating needle and looper operating slide g provided with pins or projections g², rock-shaft g⁴ having arms g³ furnished with vibrating bar g' engaging said projections g², slotted arm g⁵ on said rock-shaft, sliding block g⁷, crank g⁸ journaled loosely on said screw and passing through said sliding block, and pawl g⁹ and ratchet g¹⁰ for locking said crank to said screw-shaft, where it revolves in one direction but not in the other, a driving-gear N, and sliding sleeve G³ on said screw-shaft G² furnished with gears G⁵ G⁶ adapted to alternately engage the driving-gear and reverse the motion of the screw-shaft, and a slide G⁶ connected to said sliding sleeve G³ and adapted to be engaged by said carriage G to reverse the motion of said screw-shaft, substantially as specified.
